UNITED STATES PATENT OFFICE.

JESSIE GERLDINE CAMPBELL AND CLARA NINA WOOLNER, OF OAKLAND, CALIFORNIA.

DESIGN FOR A GARMENT.

46,590.

Specification for Design.

Patented Oct. 27, 1914.

Application filed April 7, 1914. Serial No. 830,307. Term of patent 3½ years.

To all whom it may concern:

Be it known that we, JESSIE GERLDINE CAMPBELL and CLARA NINA WOOLNER, citizens of the United States, residing at Oakland, in the county of Alameda and State of California, have invented a new, original, and ornamental Design for Garments, of which the following is a specification, reference being had to the accompanying drawing, forming part thereof.

The figure is a view in perspective of a garment, showing our new design.

We claim—

The ornamental design for a garment, as shown.

In testimony whereof we affix our signatures in presence of two witnesses.

JESSIE GERLDINE CAMPBELL.
CLARA NINA WOOLNER.

Witnesses:

R. M. AYARZO,
W. A. STOCK.
